UNITED STATES PATENT OFFICE

2,490,313

TOY AIRPLANE CONTROL

Honore L. Meister, Houston, Tex.

Application July 9, 1947, Serial No. 759,843

2 Claims. (Cl. 46—77)

1

This invention relates to new and useful improvements and structural refinements in controls for toy aeroplanes, more specifically, in controls which constitute a component of the device disclosed in the United States Patent No. 2,292,416, granted to M. E. Walker on August 11, 1942.

In particular, this invention concerns itself with the particular control for elevating and depressing the elevators of the empennage, which, in the device of Walker are actuated by means of a rod connected to a crank pivoted in the fuselage. However, inasmuch as the effective movement of the elevator actuating rod is directly proportional to the movement of the crank, persons who are unskilled in handling the aeroplane often experience the tendency to actuate the crank too abruptly, thereby losing the relatively gradual touch and finesse in controlling the aircraft.

Steps have been taken to rectify this disadvantage by providing two or more points on the actuating crank to which the elevator rod may be selectively connected. As a result, the operator was able to use more abrupt or a more gradual control of the elevators, simply by attaching the elevator rod further from or closer to the pivot of the actuating crank.

However, an adjustment of this nature necessarily had to be undertaken while the aeroplane was on the ground and no means were provided for effecting such adjustment in flight.

It is, therefore, the principal object of the instant invention to eliminate the above outlined disadvantages by providing an elevator control which embodies means for varying the movement of the elevator with respect to the actuating crank or lever in a predetermined, variable ratio, which ratio may be effectively varied during flight.

A further object of the invention is to provide an elevator control which is simple in construction, which may be easily and conveniently manipulated, and which may be readily applied to new model aircraft, as well as those already in existence.

An additional object of the invention is to provide an elevator control which is light in weight, which will readily lend itself to economical manufacture, and which is otherwise well adapted for the purpose for which it is intended.

With the above more important objects in view and such other objects as may become apparent as this specification proceeds, the invention consists essentially of the construction and arrange-

ment of parts as shown in the accompanying drawings in which:

Figure 1 is a fragmentary top plan view of an aeroplane, partially broken away to illustrate the invention therein;

Figure 2 is a perspective view of the control connected to the elevators;

Figure 3 is a top plan view of the control; and

Figure 4 is a cross sectional view, taken substantially in the plane of the line 4—4 in Figure 2.

Like characters of reference are used to designate like parts in the specification and throughout the several views.

Referring now to the accompanying drawings in detail, the invention consists of an elevator control designated generally by the reference character 10, such as may be conveniently and effectively employed for raising and lowering the elevators 11 of a miniature aeroplane 12.

This aircraft may be of any suitable type and includes a fuselage 13 to the tail portion of which the elevators 11, which are adapted for simultaneous movement, are hingedly connected.

In effect, the elevators 11 may be rigidly secured to a shaft 13 which also carries a crank 14 disposed between the two elevators, as is indicated in Figure 2. An elevator rod 15 extends longitudinally in the fuselage 13, the end portions

of the rod being angulated as at 16 and 17, and the end portion 16 being pivoted to the crank 14, as will be clearly understood.

The control unit 10 includes a strip-like base plate 18 which is rigidly secured in the fuselage 13, and a substantially T-shaped lever 19 is pivoted by means of a screw 20 to the plate, as will be clearly apparent. It should be noted that the pivot screw 20 is disposed at the junction of the three arms of the T-shaped lever, while a pair of

remote control cords 21 are connected to the longitudinally aligned arms, as indicated at 22. The cords 21, of course, are of sufficient length to extend to the operator, so that the aircraft may be effectively controlled while in flight.

The remaining, that is, the laterally projecting arm of the lever 19 is formed with an open slot 23 in which a roller 24 is slidably positioned. This roller is of a disc-like configuration and is formed in the periphery thereof with a V-shaped groove 25, while the longitudinal edges of the slot 23 are chamfered to provide what may be called knife edges 26. These knife edges engage the groove of the roller, whereby the latter is not only effectively retained in position in the slot,

but friction resulting from the sliding or rotation thereof is substantially minimized.

The roller 24 is rotatably mounted between a pair of spaced parallel members constituting what may be called a crank 27, this crank being pivoted to the aforementioned base plate 18 by means of a further screw 28. The roller 24 itself is mounted upon the angulated portion 17 of the aforementioned rod 15, which angulated portion extends through the members of the crank 27, as will be clearly apparent.

Finally, it may be mentioned that a pair of up-standing stop pins 29 are provided on the base plate 18 for the purpose of restricting the extent of movement of the lever 19.

When the invention is placed in use, the elevators 11 are intended to be disposed in a horizontal position when the pivot elements 20, 17 and 28 are in alignment, as illustrated in Figures 1 and 2.

However, assuming that one of the cords 21 is pulled in the direction of the arrow 30, the lever 19 will be swung about the pivot 20 in the direction of the arrow 31 and, at the same time, the crank 27 will be moved in the direction of the arrow 32. This is illustrated in the accompanying Figure 3, wherein it will be noted that the movement of the members 19 and 27 will be accompanied by the outward sliding movement of the roller 24 in the slot 23, whereby the distance of the roller 24 from the pivot 20 will become progressively greater as the movement of the lever 19 continues. Needless to say, a similar condition presents itself when the lever 19 is swung in the relatively opposite direction, that is to say, to the right-hand side of the dead center line (4—4) normally established by the pivots 20, 17 and 28, as viewed in Figure 2.

The essence of the invention resides in the predetermined, variable ratio of the extent of movement of the crank 27 with respect to that of the lever 19, this, of course, being facilitated by the sliding of the roller 24 in the slot 23. That is to say, when the pivots 20, 17 and 28 are disposed in alignment, the roller 24 will be as close to the pivot 20 as possible, and relatively large movement of the lever 19 will impart a relatively small movement to the roller 24, and through the medium of the rod 15, to the elevators 11. In this manner, finesse of control and precision flying at take-off and landing will be facilitated.

However, when the aircraft is in flight, considerable movement may be imparted to the lever 19, and since under such circumstances the roller 24 will be moved in the slot 23 as far as possible

from the pivot 20, abrupt movement will be imparted to the elevators 11 by virtue of the increased leverage. This abrupt control will, of course, be highly effective when encountering obstacles or during stunt flying.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

- 20 1. In a toy aeroplane including a fuselage and a pair of simultaneously movable elevators, an elevator control comprising a base plate mounted in said fuselage, a crank pivoted at one end thereof to said plate and operatively connected at its free end to said elevators, a substantially T-shaped lever having a pivot at the junction of its arms and being attached by said pivot to said plate, a pair of remote control cords connected to the longitudinally aligned arms of said lever, the laterally projecting arm of said lever being formed with an open slot, and a rotatable roller mounted on said free end of said crank, said roller engaging the edges of said slot for guided movement of said crank therewithin.
- 25 2. The device as defined in claim 1 in which the periphery of said roller is formed with a V-shaped groove, the longitudinal edges of said slot being chamfered and providing knife edges to engage said roller within said groove.
